CLAIM

The ornamental design for a valve handle for a container, as shown and described.

DESCRIPTION

FIG. 1 is a top perspective view of the valve handle for a container, showing my new design;

FIG. 2 is a top plan view thereof;

FIG. 3 is a left side elevation view thereof;

FIG. 4 is a right side elevation view thereof;

FIG. 5 is a bottom plan view thereof;

FIG. 6 is a rear side elevation view thereof; and,

FIG. 7 is a front side elevation view thereof.

The broken lines shown illustrate portions of the valve handle for a container and form no part of the claimed design.

1 Claim, 7 Drawing Sheets
